UNITED STATES PATENT OFFICE.

JAMES B. FISHER AND JAMES E. DE LONG, OF WAUKESHA, WISCONSIN, ASSIGNORS TO
WAUKESHA MOTOR COMPANY, OF WAUKESHA, WISCONSIN, A CORPORATION OF
WISCONSIN.

DRIVING UNIT.

Application filed October 29, 1925, Serial No. 65,531. Renewed May 25, 1928.

Our invention relates to driving units, and particularly to a portable driving unit comprising an internal combustion engine, a reduction gearing, and a jack shaft structure 5 all mounted on a common support. The object of the invention is to provide a simple, compact and substantial arrangement in which the high speed of the engine is reduced down to a powerful rotation of the jack shaft, 10 one of the features being the parallel arrangement of all the shafts so that balanced operation results. The various features of our invention will become apparent from the following detailed description in connection 15 with the drawings, in which

Fig. 1 is a side elevational view;

Fig. 2 is a plan view; and

Fig. 3 is an end view.

The supporting base of the driving unit 20 comprises the front main beam 1, the side main beams 2 and 3, and intermediate longitudinal and transverse beams 4 and 5, respectively. Mounted on the base between the beams 2 and 4 is the internal combustion engine E, whose crank shaft structure 6 terminates in a pinion 7. The shaft extends through the housings 8 and 9, the pinion being within the housing 9. Journaled in the front and rear walls of the housing 9, to one 25 side of and parallel with the engine shaft, is the counter-shaft 10, which within the housing 9 has secured thereto the annular gear 11 with which the engine pinion 7 meshes, as clearly shown in Fig. 2. Outside of the housing 9, the countershaft 10 carries the driving pinion 12 and the shaft may also carry a fly-wheel 13.

Mounted on the beams 1 and 5, respectively, 30 are the pedestal bearing structures 14 and 15, in which is journaled the jack shaft 16, which is parallel with the engine shaft and with the counter-shaft 6 and 10, respectively. In alignment with the driving pinion 12 the jack shaft carries the large gear 17 which meshes 35 with the pinion, and this gear and pinion are enclosed in a housing structure 18 suitably supported on the unit base. The arrangement is clearly shown in Fig. 2, and also in Fig. 3 where the fly-wheel has been omitted. 40 By means of the annular gear 11 and the large gear 17, the high speed of the engine pinion is reduced down to slow and powerful rotation of the jack shaft 16. The jack shaft is therefore capable of performing very heavy

service. Secured to the outer end of the jack 55 shaft, I have shown a crank structure 19 provided with a crank pin 20 which is adjustable on the crank structure by means of a series of supporting holes 21. In practice this crank structure has been connected with the work- 60 ing beam of large drills or pumps used in the oil fields, and can be as readily used for other purposes. We also provide on the jack shaft a sprocket pinion 22, from which apparatus may be driven by means of a chain. To 65 facilitate the application of the sprocket wheel, it is longitudinally adjustable on the jack shaft by means of the groove 23 and set screws 24.

All the supporting parts, bearing parts and 70 housing parts are made heavy and strong in order to withstand the heavy work required, and as all the shafts are parallel, transmission friction is reduced to a minimum and the unit operation is balanced and smooth. The 75 fly wheel 13 on the end of the counter-shaft 10 further stabilizes and balances the operation. The strong and rigid construction of the supporting base structure permits the unit to be 80 readily transported or shifted from one position to another so that connection can be very readily made with the work to be performed.

We have thus produced a very powerful and efficient driving unit, and we claim as 85 follows:

1. A unitary driving structure comprising a supporting base, an internal combustion motor mounted on said base along one side thereof, a gear pinion secured to the outer 90 end of the motor driving shaft structure, a housing secured to the motor frame enclosing said gear pinion, a counter shaft journaled in said housing parallel with the motor shaft structure, an internal gear on said counter 95 shaft within said housing and meshing with said pinion, a transmission pinion on the counter shaft outside of said housing, bearing supports mounted on said base along the opposite side thereof, a jack shaft journaled in 100 said bearing structures and extending parallel with said motor shaft structure, a gear carried on said jack shaft and meshing with said transmission pinion, a housing supported on said base and enclosing said transmission 105 pinion and said shaft gear, a power transmission element in the form of a crank structure secured to the outer end of said jack shaft,

and a transmission gear shiftable on said jack shaft between said bearing structures.

2. A unitary driving structure comprising a supporting base, an internal combustion motor mounted on said base along one side thereof, a gear pinion secured to the outer end of the motor driving shaft structure, a housing secured to the motor frame enclosing said gear pinion, a counter shaft journaled in said housing parallel with the motor shaft structure, an internal gear on said counter shaft within said housing and meshing with said pinion, a transmission pinion on the counter shaft outside of said housing, bearing supports

mounted on said base along the opposite side thereof, a jack shaft journaled in said bearing structures and extending parallel with said motor shaft structure, a gear carried on said jack shaft and meshing with said transmission pinion, a housing supported on said base and enclosing said transmission pinion and said shaft gear, and a power transmission element in the form of a crank structure secured to the outer end of said jack shaft.

In witness whereof, we hereunto subscribe our names this 21st day of October, 1925.

JAMES B. FISHER.
JAMES E. DE LONG.
